UNITED STATES PATENT OFFICE

131,492

DESIGN FOR A DIAL MONEY CLIP OR SIMILAR ARTICLE

Hilda D. Lee, New York, N. Y.

Application January 10, 1942, Serial No. 105,103

Term of patent 7 years

To all whom it may concern:

Be it known that I, Hilda D. Lee, a citizen of the United States of America, residing in New York city, county of New York, and State of New York, have invented a new, original, and ornamental Design for a Dial Money Clip or Similar Article, of which the following is a specification, reference being had to the accompanying drawing, forming part thereof.

Fig. 1 is a plan view of a dial money clip or similar article showing my new design.

Fig. 2 is an edge view thereof.

I claim:

The ornamental design for a dial money clip or similar article, substantially as shown.

HILDA D. LEE.
